ARTHUR L. PRIMEAU, OF FITCHBURG, MASSACHUSETTS.

FLUID-MEASURING PUMP.

1,116,732.

Specification of Letters Patent.

Patented Nov. 10, 1914.

Application filed April 4, 1913. Serial No. 758,910.

To all whom it may concern:

Be it known that I, ARTHUR L. PRIMEAU, a citizen of the United States, residing at Fitchburg, in the county of Worcester and State of Massachusetts, have invented certain new and useful Improvements in Fluid-Measuring Pumps; and I do hereby declare the following to be a full, clear, and exact description of the invention, such as will enable others skilled in the art to which it appertains to make and use the same.

This invention comprehends improvements in fluid measuring pumps and has for its primary object the provision of a double acting pump of this nature, which shall be of extremely simple construction, cheap to manufacture, and reliable in operation.

A further object of the invention resides in the provision of a double acting fluid measuring pump having a vertically extending working or piston cylinder, intake and discharge headers or hollow members in communication therewith, and novelly constructed valves for closing the passageways leading into and from the interior of the working cylinder.

In the preferred form of the invention, the working cylinder and the hollow intake and discharge members are integrally connected. Part of the valve-controlled passageways extend horizontally and conduct the fluid being pumped from the interior of the hollow intake header or member into the pump cylinder while the rest of said passageways conduct the fluid from the interior of the pump cylinders into the discharge header or hollow member. All of the valves for controlling the flow through said passageways are located within the headers. In other words, the fluid flows past the intake valves before passing through the horizontally extending passageways leading to the pump cylinder and it passes through the horizontally extending passageways leading from the pump cylinder prior to flowing past the outlet valves.

With these and other objects in view, as will become more apparent as the description proceeds, the invention consists in certain novel features of construction, combination, and arrangement of parts, as will be hereinafter described and claimed.

For a complete understanding of my invention, reference is to be had to the following description and accompanying drawings, in which,

Figure 1 is a top plan view of my improved pump, and, Fig. 2 is a vertical sectional view therethrough, showing a portion of the casing which contains the operating mechanism, which latter is not shown.

In the preferred embodiment of my invention, as illustrated in the drawings, 5 designates a vertically extending piston or working cylinder, 6 the intake header or 65 hollow member, cylindrical in shape, and 7 the discharge header or hollow member, which is also cylindrical in shape. The working cylinder and the hollow intake and discharge members are preferably cast integrally, thus providing a body or main casting, and the intake and discharge headers or members are shown as being positioned upon the exterior of the working cylinder and on opposite sides thereof.

The last mentioned cylinder is closed at its upper end by a removable wall 8, which is secured in position by means of suitable fasteners 9. Hollow sleeve-like projections 10 are integrally formed upon the exterior of the wall 8 to receive the supporting rods 11, which are rigidly secured thereto. These rods extend upwardly through a casing, generally designated 12, and are secured therein by means of 85 nuts 13. The wall 8 is centrally apertured to permit the passage therethrough of a piston rod 14 to the lower end of which a piston 15 is secured by means of nuts 16. A stuffing box 17 of the usual construction, 90 surrounds the piston rod 14 upon the exterior of the cylinder. The means which I have provided for supporting the pump make it possible to so adjust the same as to bring the piston rod 14 in accurate alignment with the operating means, not shown. The bottom wall 18 is formed integrally with the cylinder and is provided with an off-set portion 19 which forms an inwardly opening recess 20 to receive the nuts 16 100 when the piston is at the limit of its downward movement.

The intake header or hollow member 6 is of a much smaller diameter than the working cylinder 5, extends the full length thereof, and communicates therewith by means of the upper and lower horizontally-extending intake-passageways 21 and 22. Liquid enters the cylinder 6 through the neck 23, to which is connected a pipe 24 that leads to a 110 suitable reservoir.

The flow of fluid through the horizon-

tally-extending passageways 21 and 22 is controlled by the sleeve puppet valves 25 and 26, respectively. These valves are respectively called upper and lower inlet valves. Each of these valves is formed with a sleeve 27, equal to the internal diameter of the cylinder 6 into which it extends. These sleeve members are formed with openings or ports 28 through which the fluid passes on its way to the working cylinder 5. Cylindrical plugs 29 and 30 close the upper and lower ends of the header or hollow cylindrical members 6. These plugs are preferably threaded into engagement with the interior of said member and are provided with wrench receiving sockets 31. Expansive spiral springs 32 engage the opposed ends of the plugs 29 and 30 and serve to hold the valves upon their seats. Both the plugs and valves are provided with tips or projections 33 for the purpose of securing the springs in position and limiting the outward movement of the valves.

The discharge header or hollow member 7 is of a somewhat larger diameter than the intake header 6, extends the full length of the working cylinder 5, and is provided intermediate its ends with a discharge neck 34, which is connected to a pipe 35 that leads to a suitable discharge point. The fluid from the working cylinder 5 enters the discharge header through the upper and lower horizontally-extending-outlet passageways 36 and 37, which lead from the upper and lower portions, respectively, of said working cylinder. Cylindrical tubular valve cages 38 and 39 are threaded into the discharge header or cylindrical member 7 and are disposed between the passageways 36 and 37. The passages through the valve cages are of a restricted diameter adjacent their outer ends, viz., at the lower end of the cage for the lower valve and the upper end of the cage for the upper valve. This cage construction provides seats for the valves 40 and 41, each of which is provided with an outwardly extending sleeve 42 having openings or ports 43 formed therein. For the purpose of holding the valves upon their seats, I provide apertured disks 44 which are secured in the inner ends of the valve cages and which are provided with outwardly projecting stems 45, which terminate in spaced relationship to the projections formed upon the opposed faces of the valves. Expansive spiral springs 46 surround the stems and by bearing against the valves serve to hold them normally upon their seats. The ends of the cylinder 7 are closed by plugs 47 and 48, similar in construction to the ones already described.

In operation, as the piston descends, the fluid is sucked into the piston or working cylinder 5 through the upper-intake passageway 21 and is forced from said

cylinder through the lower-outlet passageway 37. During this movement of the piston, the lower-inlet valve 26 that controls the flow from the inlet header into the lower-horizontally-extending intake passageway and the upper outlet-valve 40 that controls the flow from the upper horizontally-extending outlet passageway into the discharge header remain seated. On the up-stroke of the piston, fluid is drawn from the intake header, past the lower intake valve into the lower horizontally-extending intake passageway, thence into the cylinder 5, and at the same time liquid is being forced from said cylinder through the upper horizontally-extending discharge passageway 36, past the upper outlet valve, into the discharge header.

From the foregoing description taken in connection with the accompanying drawings, it will be seen that I have provided a fluid measuring pump of extremely simple construction, in which the inlet valves are located entirely within the inlet headers and the outlet valves are located in the discharge headers and said valves are therefore protected from injury. If desired, the plugs which close the ends of the cylinders 6 and 7 may be soldered or otherwise rigidly secured in position so that it will be impossible for anyone to tamper with the valves. It is to be noted that a very limited movement of the valves is sufficient to bring the ports formed in the sleeves thereof into such position as to permit the fluid to flow into or from the main cylinder 5 and this is an important feature of my invention. The projections formed on the exterior surfaces of the valves are provided with slots to receive a tool whereby the valve may be ground upon their seats in order to insure a perfect fit.

While in the body of the specification and in the claims thereof a pump is described as having a vertically-extending pump cylinder and horizontally-extending passageways, still it is to be understood that any pump which can be positioned so that it can satisfy the combination of elements defined in the claim, will be within the spirit and scope of the invention.

It is to be understood that while I have shown and described the preferred embodiment of my invention, I do not wish to be limited to this exact construction, combination, and arrangement of parts, but may make such changes as will fall within the spirit and scope of the invention.

Having thus described my invention, what I claim is:

1. A pump having a vertically-extending working cylinder, a piston therein, a hollow intake member, a hollow discharge member, upper and lower intake valves in said intake member and upper and lower outlet valves

- in said discharge member, said pump being provided with upper and lower horizontally-extending passageways leading from the interior of said hollow intake members to said 5 working cylinder, and upper and lower horizontally-extending passageways leading from the interior of said working cylinder to the interior of said hollow discharge member.
- 10 2. A pump having in combination with a vertically movable piston of a cast metal body comprising a hollow intake member of cylindrical formation, a piston cylinder and a hollow discharge member of cylindrical formation, upper and lower intake valves located within the intake member, and upper and lower outlet valves located within the discharge member, said cast body being provided with four horizontally-extending 15 passageways, one leading from the interior portion of the intake member to the lower interior portion of the piston cylinder, another from the interior portion of the intake member to the upper interior portion of the pump cylinder, another from the lower interior portion of the pump cylinder to the interior of the discharge member, and another from the upper interior portion of the pump cylinder to the interior of the discharge member, the valves being constructed and arranged so that as the piston is raised 20 fluid flows into the piston cylinder, but only from the intake member past the lower intake valve, thence through the corresponding horizontally-extending passageway, and fluid is discharged from said cylinder into the discharge member, but only through the upper horizontally-extending discharge pas-
- sageway past the corresponding outlet valve, the valves also being constructed and arranged so that as the piston is lowered fluid flows into the piston cylinder, but only from the intake member past the upper intake valve, thence through the corresponding horizontally-extending passageway, and fluid is discharged from said cylinder into the discharge member, but only through the lower horizontally-extending discharge passageway past the corresponding outlet valve. 25
3. A pump comprising a casing which is provided with a passageway, a tubular cage located within said passage and secured in place in said casing in a manner to prevent leakage between said casing and said cage, past the latter, a valve slidably mounted in 30 said cage for controlling the flow through said passageway, said cage being provided with a seat for said valve and also carrying an apertured disk or spider, and a spring located between said disk and said valve for 35 forcing the latter against its seat, the pump casing being provided with a removable plug which is positioned so that access to said cage is permitted when said plug is removed, the cage being positioned within the 40 pump casing so that the inlet and discharge ends of the cage are always in contact with the fluid in said passageway when the pump is being operated.

In testimony whereof I affix my signature 70
in presence of two witnesses.

ARTHUR L. PRIMEAU.
